GUINEVERE WINCHESTER, OF LOS ANGELES, CALIFORNIA

DESIGN FOR A COMBINED TABLE LAMP AND LIGHT SCREEN

Application filed July 15, 1930. Serial No. 36,353. Term of patent 3½ years.

To all whom it may concern:

Be it known that I, GUINEVERE WINCHESTER, a citizen of the United States, residing at 4970 Cromwell Ave., Los Angeles, in the county of Los Angeles and State of California, have invented a new, original, and ornamental Design for a Combined Table Lamp and Light Screen, of which the following is a specification, reference being had to the accompanying drawing, forming part thereof.

The Figure 1, is a perspective view of a combined table lamp and light screen, showing my new design.

The Figure 2, is a top view of a combined table lamp and light screen, showing my new design.

I claim:

The ornamental design for a combined table lamp and light screen substantially as shown.

GUINEVERE WINCHESTER.
